MEANS OF REGULATING FLOW OF FLUID
WITHIN A WELL

Mordica O. Johnston and Wilbur F. Bettis, Glendale, Calif.; said Bettis assignor to said Johnston

Application April 15, 1937, Serial No. 137,058

8 Claims. (Cl. 166—1)

This invention relates to well equipment, and particularly pertains to means of regulating flow of fluid within a well.

In the operation of various well tools designed to establish control or measure the production of oil wells it is often necessary to provide a device by which the fluid flow within the well may be maintained or controlled. This is especially true in connection with the operation of devices for testing the formation yield of a well. In such cases a formation tester carrying a packer is lowered into a well on a drill string. The packer is then set and a valve is suddenly opened, such as by the action of the go-devil. As a result the fluid pressure within the well surges upwardly through the anchor pipe, the packer, and the testing tool into the supporting drill string. At this time the packer has excluded the pressure of the head of liquid standing above the packer within the well from the area being tested beneath the packer, and when the valve is opened there is a possibility that the surge of fluid, both oil and gas, will be such as to relieve the supporting pressure within the area below the packer and cause it to cave in. It is therefore desirable to gradually increase the flow of fluid from the area below the packer and into the drill string by controlled means whereby any sudden evacuation of the tested area will be eliminated, and the flow of fluid may be progressively increased in volume.

It is the principal object of the present invention therefor to provide a method of controlling fluid flow by a flow device adapted to be interposed at some point between the packer and the top of the well, and which device may be actuated from the top of the well to control and vary the flow of fluid therethrough.

It also often occurs that the fluid within the well is filled with silt and sand which might clog the fluid passageways of a control device and it is another object of the present invention to provide a method and means of fluid control whereby the possibility of clogging will be eliminated thus insuring accurate control and regulation of flow.

It is another object of the present invention to provide a fluid flow control device which may be opened, regulated and closed a plurality of times by rotation in one direction only, thus eliminating the necessity of withdrawing and resealing the valve or rotating in a counter direction.

The present invention contemplates the provision of a fluid flow device which may be inter-

posed between joints of a drill string, or at other points between tools or appliances carried by the drill string, and which device may be manipulated from the top of the well to be opened, closed and set to any desired degree.

The invention is illustrated by way of example in the accompanying drawings, in which:

Fig. 1 is a view in elevation showing a method of use of the flow device with which the present invention is concerned.

Fig. 2 is an enlarged view showing the upper portion of the preferred form of the flow device with which the present invention is concerned.

Fig. 3 is an enlarged view similar to Fig. 2 showing the lower portion of the preferred form of the adjustable flow device.

Fig. 4 is a view in transverse section through the flow device as seen on the line 4—4 of Fig. 3.

Fig. 5 is a schematic view showing the developed circumference of the interlocking means 20 within the flow device as seen on the line a of Fig. 4.

Fig. 6 is a fragmentary view in section showing the upper end of another form of the invention.

Fig. 7 is a view in transverse section through the device as seen on the line 7—7 of Fig. 6.

Fig. 8 is a view in transverse section through the flow device as seen on the line 8—8 of Fig. 6.

Fig. 9 is a view in section and elevation showing another form of flow device.

Fig. 10 is a view in transverse section as seen on the line 10—10 of Fig. 9 and showing the fluid passageways.

Referring more particularly to the drawings, 35 11 indicates a drill stem to which a trip valve 12 is connected. This valve is preferably of the type within which a valve element is held normally in a closed and locked position, and is released and opened by the dropping of a go-devil 40 from the top of the well and through the drill stem until it strikes the valve mechanism and opens the valve, the said trip valve being thereafter locked in its opened position. Carried at the lower end of the trip valve housing is a suitable length of drill string 13 to which an adjustable flow device 14 is connected and with which device the present invention is particularly concerned. Suitably connected below the flow device is the main valve structure of a well testing 50 tool 15, the tool being of the general type shown in Patent No. 2,073,107 issued to M. O. Johnston, co-inventor of the instant application entitled Well testing method and apparatus therefor. Interposed between the flow device 14 and the 55

main valve structure of the testing tool 15 is a drill string section 16 which serves as a fluid chamber for a purpose to be hereinafter described. There is usually assembled with the main valve structure of the testing tool 15 an equalizer valve structure 17 which carries a packer 18 at its lower end. The packer 18 in turn carries a perforated anchor pipe 19 by which fluid may be directed through the packer 18 and then upwardly through the equalizer valve structure 17, and successively through the various tools previously described. The valve of the equalizer valve structure 17 has the usual function of being closed when the packer 18 is seated so that fluid from the column of fluid within the well bore will be sealed off completely by the packer 18 and is opened when the drill string is lifted prior to pulling the packer 18 from its seat. This action will equalize the pressure within the well above and below the packer 18 and will make it possible to more readily withdraw the packer 18 from the hole.

The form of the flow device 14 shown in Figs. 2 and 3 include an upper sleeve portion 20, a coupling element 21 having a threaded pin 22 extending into the sleeve portion 20, and a pin 23 extending into a body member 24. The sleeve portion 20 at its upper end is interiorly threaded for the reception of the upper threaded end of the section of the drill string 13. The lower end of the body member 24 is formed with a pin 25 which is threaded into the upper end of a packing sleeve 26. The packing sleeve 26 slidably receives a tubular mandrel 27 which extends downwardly and is threaded into a coupling 28 by which it may be attached to various oil well tools as illustrated at 15 in Fig. 3. A packing gland is formed in the member 26 and receives packing 29 which is held in position by a packing nut 30. The upper end of the mandrel 27 is formed with an enlarged head 31 cut away at diametrically opposite sides as indicated at 32 and 33 to form keyways in Fig. 4 of the drawings. Thus, as shown in Fig. 5 the head provides two keyway guides 34 and 35 which cooperate with lugs 36 and 37 and with lugs 38 and 39, both of which sets of lugs are carried upon the inner wall of the body member 24 to facilitate in locking the tubular mandrel 27 in position, and for a purpose to be hereinafter described. The upper end of the tubular mandrel 27 is formed with clutch jaws 40 extending diametrically across the end wall of the mandrel and adapted under some circumstances to engage jaws 41 projecting from a nut 43 carried on the lower end of a tubular shaft 42 which extends downwardly through the members 20, 21 and 24. The nut 43 is exteriorly threaded and engages a thread 44 formed in the inner wall of the body 21 member 24. The coupling section 21 is formed with a packing gland receiving packing 45 which circumscribes the tubular shaft 42 and forms a fluid packing therearound. A packing nut 46 holds the packing 45 in position and is threaded into the pin 23 of the coupling 21. The inside diameter of the upper tubular member 20 is relatively large and forms a fluid space 47. Into this space the upper end of the tubular shaft 42 projects. A central passageway 48 extends through the tubular shaft 42 and communicates at its upper end with a valve cage 49 through ducts 50. The valve cage carries a valve ball 51 held upwardly against a seat 52 by a spring 53. The seat is held in position by a tubular nut 54. The lower end of the passageway 48 through the tubular shaft 42 communicates with a fluid

space 55 within the member 24. This space in turn communicates with a central passageway 27 through the tubular mandrel 27. The wall of the tubular shaft 42 adjacent to its upper end is formed with a plurality of radially disposed threaded openings 56 which receive flow bean buttons 57 having a central passageway 58 extending therethrough, the passageways progressing in diameter from the outermost part to the innermost part of members 57. It is understood that as manner to be hereinafter explained the tubular shaft 42 has relatively longitudinal movement with relation to the coupling 21 and the body member 24, this movement acting to project the tubular shaft 42 upwardly into the space 47 within the member 20 and to consecutively uncover the openings 56 to establish communication between the space 47 and the internal passageway 48 of the tubular shaft. It will also be understood that the buttons 57 may be interchangeably mounted within the openings 56 by a tubular nut 59. Under normal conditions the mandrel 27 and the body member 24 are interlocked against relative longitudinal movement. This construction and arrangement is more particularly shown in Figs. 3, 4 and 5. As heretofore stated the head 31 of the mandrel 27 is longitudinally cut to form the keyways 32 and 33 which define the opposite edges of lugs 34 and 35, and the body member 24 is formed with a relatively narrow pair of lugs 36 and 37 and a relatively wide pair of lugs 38 and 39. The lugs 36 and 37 are normally held against the lugs 34 and 35. The lugs 34 and 35 when in these positions are beneath the relatively long lugs 38 and 39 carried by the member 24, and upon relative rotation they move to space 60 occurring between the lugs 38 and 39 after which there may be relatively longitudinal movement of the mandrel 27 and the member 24. Attention is directed to the fact that after the tubular shaft 42 is moved to its uppermost position it is desirable to lock this shaft and the body member 24 against rotation or longitudinal movement. This is accomplished by a radially disposed lock pin 61 carried in a bore 62 in the nut 43. The pin is urged outwardly by a spring 63 and when it is in register with a recess 64 in the wall of the member 24 it will extend thereinto and lock the nut 43 against movement. The outer end of the recess 64 is preferably closed by a countersunk nut 65 which makes it possible to reset the pin after use.

In operation of the form of the invention shown in Figs. 2 to 5 inclusive, it will be understood that the device may be used as a flow regulating device alone, or that it may be used in combination with testing tools and such structures as are shown in Fig. 1 of the drawings. The specific operation of the structure shown in Figs. 2 to 5 inclusive is as follows: When the flow device 14 is placed into the well the tubular mandrel 27 is in its lowermost position with the lugs 34 and 35 held against the lugs 36 and 37 and disposed beneath the lugs 38 and 39. Rotation of the drill string to the right will cause the members to be maintained in this position as the tool is lowered into the hole. At this same time the nut 43 is in its lowermost position with relation to the thread 44 and the upper end of the tubular shaft 42 is disposed so that the uppermost flow bean 57 is above the upper end of the coupling 21. The valve ball 51 which is a part of an emergency circulation valve is positioned on its seat 52. When it is desired to open the flow device the drill string is rotated in a counterclockwise direction 75

tion. This causes the spaces 60 to register with the lugs 34 and 35 so that the member 24 may move downwardly until the head 31 clears the lugs 38 and 39, after which the body member 24 may 5 rotate freely with relation to the mandrel 27 and its head 31. When in this position the jaws 41 on nut 43 may move into register with the clutch jaws 40 so that the nut 43 will be held against rotation. Continued rotation will cause 10 the body member 24 to move downwardly on the nut 43 and the upper end of the tubular shaft 42 to project above the coupling 21. This insures that the flow bean buttons 58 will be uncovered progressively and will create a progressively increasing area through which fluid may flow from the passageway 48 to the space 47 in the member 20. Attention is directed to the fact that the 15 normal direction of fluid flow is outwardly through the opening 58 and into the space 47, and that furthermore there is a considerable distance 20 between the inner face of the wall of the member 20 and the outlet mouths of the openings 58. This will permit some of the force of the fluid pressure to be dissipated before the fluid jets 25 impinge against the wall of the member 20. Thus the abrasive action of the fluid will be materially diminished. It will also be evident that by this arrangement the wall of the member 20 might be readily patched by welding in the event 30 that the abrasive action of the fluid should cut an opening entirely through this wall. When the flow device has been manipulated to place all of the flow beans 57 in communication with the space 47 and beyond the upper end of the member 35 21 the lock pin 61 carried by the nut 43 will move to a position of register with the recess 64 in the member 24. This will lock the nut 43 against rotation with relation to the member 24 and make it possible for rotation or longitudinal 40 manipulation of the flow device to be brought about as a unit for any other desired operations. In the event that an emergency condition arises 45 which requires the circulation of fluid through the drill string and the flow device, this may be accomplished by pumping the fluid downwardly with the drill string, to depress the spring 53 and move the ball 51 from its seat so that fluid may flow downwardly through the cage 49, the passageway 48 in the tubular shaft 42, and the tubular mandrel 27.

Referring more particularly to Figures 6, 7 and 8 of the drawings the adjustable flow device is shown comprising a tubular mandrel 66 which is threaded into the lower end of the housing 66' of the trip valve 12. This mandrel is enlarged at its lower end to form a cylinder head 67 carrying threads 68. The mandrel extends into a sleeve 69 having interior threads 70 to receive the threads 68 of the head 67. Adjacent the upper end of the sleeve 69 an annular shoulder 71 is formed within the bore of the sleeve and when in its upper position the head 67 abuts against and lies beneath this shoulder. A counterbore 72 is formed above the shoulder containing packing which is held in position by a packing nut 73. The tubular mandrel 66 moves through the gland and packing and is thereby held leak-proof. The mandrel head 67 is formed with a central fluid circulating passageway 74 therethrough which terminates at its lower end in a threaded counterbore 75. The threaded counterbore receives a tubular valve stem 76 which extends downwardly through the sleeve 69 and the coupling 77. The upper end of the coupling 77 is threaded into the sleeve 69 at 78. The low-

er end of coupling 77 is threaded at 79 and extends into a tubular housing 80 forming a part of the fluid chamber 80'.

The coupling 77 is formed with a central bore 81 at its upper end which fits snugly around the valve stem 76 while permitting the valve stem to reciprocate therethrough. The bore 81 is enlarged as indicated at 82 throughout its lower length to receive suitable packing 83 and has a threaded mouth 84 within which a packing nut 10 85 is secured. The packing nut is formed with a central bore which also fits snugly around the valve stem 76, and cooperates therewith in providing a reciprocating valve structure. The valve action is obtained by forming a plurality of radial 15 perforations or passageways 86 through the wall of the valve stem 76 so that communication may be established between the space outside of the valve stem and the longitudinal passageway 20 87 within the valve stem 76. These passageways are progressively increased in size and may be successively moved to points below the valve bushing 85 in order to uncover them and to permit fluid which may be within the tubular housing 80 to flow into the passageway 87 of the valve stem 76 and then upwardly through the tubular mandrel 66 and into the testing tool 15, or other element connected therewith. In practice it is desirable to progressively increase the diameters of these openings 87 from approximately 30 32nd of an inch upwardly and it will be evident that as a greater number of passageways 86 are disclosed the flow of fluid may be accurately controlled.

Attention is directed to the fact that an end wall is formed at the lower end of the valve stem 76 having a passageway 88 extending downwardly therethrough. This passageway is normally closed by a ball valve 89 which is held in place by an expansion spring 90. This spring 40 rests at its lower end upon an adjusting disc 91 and an adjusting screw 92 abuts against it. The screw 92 and the spring 90 are carried within a valve cage 93 which has openings 94 in its side to permit fluid flow when required. The valve 89 is an emergency valve which permits free circulation of fluid to take place downwardly, irrespective of the adjusted position of the fluid control structure, when the pump is operated at the top of the well and an emergency operation 50 is required to re-establish circulation through the tool at a time where there is a possibility that the tool and its packer might become stuck in the well.

In order to hold the tubular mandrel 66 and 55 the sleeve 69 against longitudinal movement with relation to each other when the shoulder 71 of the head 67 is in its uppermost and abutting position against the shear pin 96, or other temporary locking means known to those skilled in 60 the art, is provided. This pin as shown in Figs. 6 and 7 of the drawings, is threaded through the wall of the sleeve 69 and has an extending portion which projects into a cavity 96' within the mandrel 66. The strength of this extending portion 65 will be determined in order to resist any normal twisting action to which the drill string and various parts are subjected.

In some instances a flow device is used to control the flow of a well without the additional use 70 of testing tools or other similar equipment. In such cases it may be desirable to establish flow then resist it to build up pressure and thereafter again establish flow. Due to the fact that the supporting string carrying the flow device is con- 75

nected by threaded joints it is desirable that the flow device shall be rotated in one direction only, and with that in mind the structure shown in Figures 9 and 10 has been provided to successively increase and decrease the flow by rotation of the flow device and its supporting string in one direction. In this particular structure the lower end of the tubular mandrel 66 may successively pass through a central bore 97 which is formed within the lower part of tubular housing 80 which is also formed with longitudinal passageways 98. A central bore 97' through the upper part of housing 80 and longitudinal passageways 99 are likewise provided in said housing. The bore 97' receives the downwardly extending end of the mandrel 66 and the valve cage 93. A space 99 occurs between the upper end of the housing 80 and the lower end of the packing nut 85 so that but one of the perforations or ports 86 will be in a position to permit a flow of fluid therethrough at a time. A space 100 is provided between the upper and lower parts of housing 80 for the same purpose as is provided by the space 99. Thus it will be evident that by continuing to rotate the mandrel 66 it will successively pass through bores 97' and 97 and will make it possible to control the flow of fluid due to placing one of the ports 86 into register with the space 99 or 100.

In one manner of operation of the present invention the adjustable flow device may be mounted as indicated in Fig. 6 of the drawings at a point between the trip valve 12, and the testing tool 15 or at some point between the testing tool 15, and the equalizer valve 17. The flow device is adjusted so that the threaded head 67 of the mandrel 66 abuts against the shoulder 71 in the sleeve 69. When in this position the shear pin 96 is properly placed to hold the tubular mandrel 66 against movement with relation to the sleeve 69. Attention is directed to the fact that when so positioned the tubular valve stem 76 had been drawn upwardly into the coupling 77 so that all or a relatively large number of the ports 86 in the tubular valve stem 76 are above the valve bushing 85. Thus there is only possibility for slight flow of fluid from the lower housing 80 into the longitudinal passageway 87 of the valve stem 76. After the packer 18 has been set in the hole on a proper shoulder it is common practice to allow the weight of the drill string 11 to move downwardly closing the parts of the equalizer valve 17 and opening the main valve within the testing tool 15. Thus the testing tool and the equalizer valve will be prepared for taking a sample. When the two valves are thus prepared it is usual practice then to open the trip valve 12 suddenly by dropping the go-devil through the drill pipe.

In some types of tools a trip valve is not used and the opening of the main valve in the test tool will suddenly admit an upward flow of fluid from the area below the packer and under the pressure there existing. It will be recognized that under such conditions the well is full of drilling fluid and that the hydrostatic head of the drilling fluid is considerable, averaging approximately one-half pound per square inch to the running foot of drilled hole. When the packer is seated the fluid within the rathole will be entrapped by the packer under the pressure of the complete hydrostatic head of the well and will be confined at this pressure until it is relieved by establishing communication between the area below the rathole and the drill stem car-

rying the testing tools. It is understood that within the drill stem normal atmospheric pressure prevails. Under either condition when the main valve of the testing tool or the trip valve is suddenly opened it will be evident that the pressure within the rathole will be instantly relieved to atmospheric pressure within the drill stem. This will cause a sudden evacuation of the area below the packer and may result in a collapse or caving in of the formation being penetrated. Under such circumstances the perforated anchor pipe may be caught within the well, or at least the perforations therein may be closed so that a free flow of fluid from the formation through the testing tool and into the drill stem may not be obtained, and the quantity of fluid entrapped will be an incorrect indication of the condition existing in the formation, and the quantity of test of the formation, whether it be liquid or gas. By interposing the adjustable flow device 14 at a point between the packer and the valve which finally controls the flow of fluid into the drill stem, it is possible first to prepare for taking the sample by opening the valve through the tester and the trip valve and thereafter opening the flow device 14 progressively. This is done by rotating the drill string, and subsequently the mandrel 66 with a force sufficient to shear off the end of the shear pin 96 so that the threaded head 67 of the tubular mandrel 66 may be rotated and screwed downwardly within the sleeve 69. This in the structure shown in Fig. 6 causes the ports 86 within the valve stem 76 to be gradually and progressively moved to a point of clearance below the packing nut 85. As a large number of ports 86 are thus lowered to a flow position the volume of fluid passing upwardly will progressively increase. This will gradually relieve the existing pressure within the formation and will thereby tend to prevent a cave-in or a surge which would fill the perforations in the anchor pipe. The result will be that an accurate quantity test can be made and will be determined by the amount of fluid entrapped within the drill string. In the form of device shown in Fig. 9 only one port 86 is involved at a time, but due to the variation in sizes the flow will be regulated and controlled.

As has been previously explained the fluid 50 which passes upwardly through the packer and the tools associated with it contains suspended solid matter which may clog the perforations in the anchor pipe 19 and may also clog the perforations or ports 86 in the control device. 55 In either event the flow of fluid constituting the incoming sample may be so resisted as to cause the similar entrapped sample to give misleading information. In order to insure against such a contingency a method has been devised, as a 60 part of the present invention, in which the length of pipe or fluid passageway occurring between the main valve 12 and the fluid control device 14 may be filled with clear water, oil or other suitable liquid. Thus as the apparatus is lowered into the well the closed main valve will prevent the leakage of a column of liquid extending up to the fluid flow device. When the main valve is opened after setting the packer this column of clear fluid will be supported upon 70 the upwardly moving column of fluid within the well, and when the trip valve is opened the clear fluid will pass upwardly through the ports 86 in the control device 14 as displaced by the upwardly moving sample of fluid from the 75

formation. The result will be that there will not be a tendency for a clogging of the ports 86 in the fluid control device 14 since an entire column of clear liquid will be forced through these ports before the ports are reached by the native fluid of the formation which might contain solids. Thus the initial inrush of native fluids to the apparatus here described will not be accomplished by a large amount of suspended solids and a more accurate and certain sample will be maintained under control.

In the event that an emergency arises which makes it necessary for circulation within the well to be re-established the mud pumps at the top of the well may be attached to the drill string and may force fluid downwardly through the drill string into the various opened valves, and also will force downwardly upon the valve ball 89 to establish communication between the center passageway 87 in the valve stem 76 and the lower passageway 88 communicating therewith. This can take place irrespective of whether or not there has been an opportunity to adjust the flow device so that circulation could be established through the ports 86 in the valve stem 76.

It will thus be seen that the method and means for regulating and controlling the flow of a well, particularly when used in conjunction with formation and casing shoe testing operations, are both simple and effective, and insure greater accuracy of tests and less hazard which might be produced by a cave-in and which might involve the loss of a tool or parts thereof.

While we have shown the preferred form of our method and means of regulating the flow of fluid within a well, it will be understood that various changes might be made in the steps of the method, and in the construction of the device embodying the invention, by those skilled in the art, without departing from the spirit of the invention as claimed.

Having thus described our invention, what we claim and desire to secure by Letters Patent is:

1. A flow device comprising a sleeve, a passageway therethrough, a valve bushing disposed at a point within said passageway, a tubular mandrel mounted within the sleeve and slideable through the valve bushing, threads formed at a point within said sleeve, a head formed on one end of said tubular mandrel, said head being threaded and engaging the threaded portion of said tubular sleeve, said mandrel being closed at its inner end and formed for a distance in its length adjacent the closed end with a plurality of axially spaced radial ports normally closed by the valve bushing and adapted to be progressively opened in sequential order as the threaded head of the mandrel moves along the threaded portion of the tubular sleeve.

2. A flow device comprising a tubular sleeve, a central passageway formed therethrough, a valve bushing disposed at a point within said passageway, a tubular mandrel mounted for longitudinal movement within the sleeve and slideable through the valve bushing, said mandrel carrying an externally threaded head at one end thereof, said mandrel being closed at the other end and formed for a distance in its length adjacent said closed end with a plurality of axially spaced radial ports normally closed by the valve bushing, threads formed for a distance within the passageway of said tubular sleeve and engaging the threaded head of the mandrel whereby relative movement between the mandrel and the sleeve will move the mandrel through the valve

bushing and progressively move the radial ports in sequential order to an unobstructed position within the sleeve.

3. A flow device comprising a tubular sleeve, a central passageway formed therethrough, a valve bushing disposed at a point within said passageway, a tubular mandrel mounted for longitudinal movement within the sleeve and slideable through the valve bushing, said mandrel carrying an externally threaded head at one end thereof, said mandrel being closed at the other end and formed for a distance in its length adjacent said closed end with a plurality of axially spaced radial ports normally closed by the valve bushing, threads formed for a distance within the passageway of said tubular sleeve and engaging the threaded head of the mandrel whereby relative movement between the mandrel and the sleeve will move the mandrel through the valve bushing and progressively move the radial ports in sequential order to an unobstructed position within the sleeve, and means temporarily locking the mandrel and the sleeve in a non-rotating position.

4. A flow device comprising a sleeve, a central passageway therethrough, a valve bushing disposed at a point within said passageway forming a fluid space within the sleeve above said bushing and a fluid space within said sleeve below said bushing, a tubular mandrel mounted for longitudinal movement within the sleeve and slideable through the valve bushing, said mandrel being closed at its upper end by an emergency valve adapted to establish flow of fluid therethrough when pressure is exerted within the fluid space, the other end of said mandrel carrying a threaded head thereon, said tubular sleeve being threaded for a distance below said valve bushing and engaging the threaded head of said mandrel, said mandrel being formed with a plurality of axially spaced radial ports normally closed by the valve bushing, said radial ports being adapted to be progressively moved in sequential order to an unobstructed position within the fluid space formed within the sleeve and above the valve bushing through relative rotational movement between the mandrel and the sleeve through their threaded connection.

5. A flow device comprising a tubular sleeve and a tubular body member, a coupling member between said tubular sleeve and body member, a central passageway formed through said members, a valve bushing disposed at a point within said coupling member, a tubular mandrel mounted for longitudinal movement within the tubular sleeve and slideable through said valve bushing, said mandrel carrying an externally threaded head at one end thereof, said mandrel being closed at the opposite end and formed for a distance in its length adjacent said closed end with a plurality of axially spaced radial ports normally closed by the valve bushing, threads formed for a distance within the passageway of the tubular body member and engaging the threaded head of the mandrel, a second mandrel positioned within the lower end of said tubular body member and having a central passageway therethrough, jaws carried on the upper end of said second mandrel adapted to engage a pair of jaws formed on the lower end of the head carried by the first named mandrel whereby relative rotational movement between the tubular sleeve the tubular body member and their coupling and the second named mandrel will cause the first named mandrel to move through the

valve bushing to progressively end in sequential order position the radial ports of the first named mandrel to an unobstructed position within the tubular sleeve when the jaws of the mandrels are in engagement.

- 5 6. A flow device comprising a tubular sleeve, a central passageway formed therethrough, a valve bushing disposed at a point within said passageway forming a fluid space within the sleeve below the valve bushing, a tubular mandrel mounted for longitudinal movement within the sleeve and slidable through the valve bushing, said mandrel carrying an externally threaded head at one end thereof the exposed end of 10 said head having a plurality of jaws formed on the face thereof, said mandrel being closed at the other end and formed for a distance in its length adjacent said closed end with a plurality of axially spaced radial ports normally closed by 15 the valve bushing, threads formed for a distance within the passageway of said tubular sleeve and engaging the threaded head of the mandrel, a second mandrel positioned within the lower end of said tubular sleeve and having a plurality of jaws formed on the upper end thereof whereby when the complementary jaws of said mandrels are in engagement relative rotation between the tubular sleeve and the second named mandrel will move the mandrel through the valve bushing and progressively move the radial ports 20 in sequential order to an unobstructed position within the sleeve.

- 25 7. A flow device comprising a tubular sleeve, a central passageway formed therethrough, a valve bushing disposed at a point within said passageway forming a fluid space within the sleeve below the valve bushing, a tubular mandrel mounted for longitudinal movement within the sleeve and slidable through the valve bushing, said mandrel carrying an externally threaded head at one end thereof the exposed end of 30 said head having a plurality of jaws formed on the face thereof, said mandrel being closed at the other end and formed for a distance in its length adjacent said closed end with a plurality of axially spaced radial ports normally closed by the valve bushing, threads formed for a distance within the passageway of said tubular sleeve and en- 35 gaging the threaded head of the mandrel a second mandrel positioned within the lower end of said tubular sleeve and having a plurality of jaws formed on the upper end thereof whereby when the complementary jaws of said mandrels are in engagement relative rotation between the tubular sleeve and the second named mandrel will move the mandrel through the valve bushing and progressively move the radial ports in 40 sequential order to an unobstructed position within the sleeve said mandrel being closed at its upper end by an emergency valve adapted to establish flow of fluid therethrough when pressure is exerted within the tubular sleeve.

45 and engaging the threaded head of the mandrel, a second mandrel positioned within the lower end of said tubular sleeve and having a plurality of jaws formed on the upper end thereof whereby when the complementary jaws of said mandrels are in engagement relative rotation between the tubular sleeve and the second named mandrel will move the mandrel through the valve bushing and progressively move the radial ports in sequential order to an unobstructed position within the sleeve and means temporarily locking the first named mandrel and the sleeve in a non-rotating position when the radial ports are in an unobstructed position within the sleeve.

50 8. A flow device comprising a tubular sleeve, a central passageway formed therethrough, a valve bushing disposed at a point within said passageway forming a fluid space within the sleeve below the valve bushing, a tubular mandrel mounted for longitudinal movement within the sleeve and slidable through the valve bushing, said mandrel carrying an externally threaded head at one end thereof the exposed end of said head having a plurality of jaws formed on the face thereof, said mandrel being closed at the other end and formed for a distance in its length adjacent said closed end with a plurality of axially spaced radial ports normally closed by the valve bushing, threads formed for a distance within the passageway of said tubular sleeve and en- 55 gaging the threaded head of the mandrel a second mandrel positioned within the lower end of said tubular sleeve and having a plurality of jaws formed on the upper end thereof whereby when the complementary jaws of said mandrels are in engagement relative rotation between the tubular sleeve and the second named mandrel will move the mandrel through the valve bushing and progressively move the radial ports in sequential order to an unobstructed position within the sleeve said mandrel being closed at its upper end by an emergency valve adapted to establish flow of fluid therethrough when pressure is exerted within the tubular sleeve.
